SNOW ICE FEEDER AND DISTRIBUTOR

Filed Jan. 5, 1942

UNITED STATES PATENT OFFICE

2,327,226

SNOW ICE FEEDER AND DISTRIBUTOR

William H. Taylor, Waukesha County, Wis., assignor to The Vilter Manufacturing Company, Milwaukee, Wis., a corporation of Wisconsin

Application January 5, 1942, Serial No. 425,673

7 Claims. (Cl. 83—63)

This invention relates generally to an improved system of handling snow or slush ice, and relates more specifically to improvements in the construction and operation of apparatus for automatically transporting, dewatering and delivering snow ice to a zone of utilization.

An object of the invention is to provide a new and useful snow ice feeding and distribution system which is simple in structure and highly efficient in operation.

It is extremely desirable in many industries, to utilize finely divided slush or snow ice in relatively dry condition and at a predetermined uniform rate in the form of a spray travelling at high velocity. While these uses are quite numerous, it is particularly desirable to thus deliver disintegrated and partially dehydrated snow ice into a constantly advancing stream of concrete aggregate such as cement and sand or gravel, in order to produce final concrete mixture while at the same time cooling the concrete mass. This practice is followed particularly in warm climates or in heated localities, and it is then also necessary to constantly produce the ice by artificial refrigeration which can be effectively accomplished with the aid of an ice-making machine such as shown in my prior patent No. 2,030,639, granted May 18, 1937. In order to insure uniformity of the final mixture, it is necessary to provide automatically functioning mechanism which is adapted to receive a variable or a constant supply of rather wet slush ice from the ice producing machine, which will effectively remove excess water from the advancing feed, and which will accurately measure and deliver the material in disintegrated and uniformly distributed spray formation into the constantly flowing stream of concrete aggregate. In most cases, the apparatus must also be adapted to furnish the properly prepared slush or snow ice in enormous quantities and at a rapid rate, so as not to interfere with or impair the rate of pouring of the concrete mixture, and while prior attempts have been made to utilize crushed ice for such purposes, these have not been entirely satisfactory in commercial use.

The present invention therefore has for an object the provision of an improved system and apparatus for continuously and most effectively converting a supply of relatively wet slush ice into a uniform spray of relatively dry snow ice travelling at high speed and in a predetermined direction.

Another specific object of the present invention is to provide an improved snow ice treating

system which is especially adapted for co-operation with an ice making machine such as shown in my prior patent, in order to prepare the ice produced by such machines for diverse commercial purposes.

A further specific object of my present invention is to provide improved mechanism for constantly removing excess moisture from an advancing stream of slush ice or the like, which is simple in construction, highly effective in actual use, and which will automatically handle large quantities of the material.

Still another specific object of this invention is to provide simple and efficient means for controlling the delivery of relatively dry snow ice from the dewatering mechanism to an ice distributor, in accurately regulated quantities.

Another additional specific object of the invention is to provide improved apparatus for quickly and most effectively disintegrating masses of snow ice, and for delivering the same in spray formation to a zone of utilization at any desired rate of speed.

A further and additional object of my invention is to provide a rotary thrower or distributor for disintegrated material such as congealed liquid, which can be manufactured and operated at moderate cost, which is dependable in operation, and which requires minimum unskilled attention.

These and other specific objects and advantages will be apparent from the following detailed description.

A clear conception of the several features constituting the present improvement, and of the construction and operation of my improved system for feeding and distributing snow ice or the like, may be had by referring to the drawing accompanying and forming a part of this specification wherein like reference characters designate the same or similar parts in the various views.

Fig. 1 is a somewhat diagrammatic and sectional side view of an improved snow ice feeding, dewatering and throwing assemblage, showing the same in action;

Fig. 2 is an enlarged transverse horizontal section through the improved ice disintegrating and throwing apparatus, taken along the line 2—2 of Fig. 1; and

Fig. 3 is a transverse vertical section through the improved means for transferring successive dewatered batches of the ice from the water remover to the thrower, the section being taken along the line 3—3 of Fig. 1.

While the invention has been shown and described herein as being especially useful in connection with the dehydration, feeding and distribution of slush or snow ice, it is not my desire or intent to thereby unnecessarily restrict the scope or utility of the improvement which is also advantageously applicable for handling other materials and for different specific uses. The terms slush and snow ice are therefore intended to include other substances having similar characteristics, and the terms concrete and granular aggregate are also to be given the broadest possible interpretation.

Referring to the drawing, the improved system shown in Fig. 1, comprises in general, an endless ice dewatering conveyor 5 formed of a continuous interconnected series of laterally curved and elongated parallel slats 6 coacting with rotary sprockets 7 and providing an upper forwardly and upwardly inclined and advancing deck 8; means such as a spout 9 and pump (not shown) for depositing a stream 10 of relatively wet slush or snow ice upon the lower portion of the advancing deck 8; a rapidly revolving cutter 11 rotatable about a horizontal axis and co-operating with the successive slats 6 to remove the caked ice therefrom; a stationary scraper blade 12 also co-operating with the advancing slats 6 to additionally remove ice particles and to direct the de-watered ice 13 downwardly; a pivotally suspended measuring and weighing trough or bucket 14 disposed beneath the directing blade 12 and being counterbalanced by an adjustable weight 15; an annular casing 16 having its upper open end 17 positioned for reception of the dry snow ice 13 from the delivery end 18 of the bucket 14 when the latter is tilted, and being provided at its lower portion with a downwardly enlarging or tapered section 19 having an adjustable peripheral outlet opening 20; and an ice disintegrating and throwing rotor 21 disposed centrally within the casing section 19 in alignment with the opening 20 and having an annular series of peripheral vanes 22 and a lesser number of upstanding central ice disintegrating blades 23 pointing upwardly into the tapered section 19.

The ice dewatering conveyor 5 is of special construction in order to quickly and effectively remove the excess water from the large quantities of slush ice which are constantly being deposited upon the upper deck 8; and the sprockets 7 which are mounted upon supporting shafts 24 may be driven in any suitable manner and at any desired speed, and are provided with peripheral teeth 25 adapted to coact with driving lugs 26 formed on the curved slats 6. The slats 6 are loosely and articulately interconnected by means of hinges 27, and are of such curvature that the successive slats provide approximately semi-cylindrical surfaces at the conveyor bends, and a series of drainage troughs or elongated hoppers 28 along the upper deck 8. The lower stretch 29 of the conveyor 5 is downwardly and rearwardly inclined, and is adapted to advance along a drainage trough 30 the lower rear end of which communicates with a liquid discharge spout 31. The formation of the conveyor slats 6 is obviously such that relatively restricted drainage slots 32 are disposed therebetween at the stretches 6, 29, but these slots 32 are materially widened when the slats pass or advance around the bends.

The rotary cutter 11 may have two or more rapidly revolving blades which co-operate with the outer surfaces of the curved slats 6 as they advance around the delivery bend, and this cut-

ter may be mounted upon a shaft 33 which is rotatable in any convenient manner. The fixed scraper blade 12 which is also co-operable with the outer surfaces of the successive curved slats 6 at the discharge bend of the conveyor 5, may be adjustably secured to the front wall of the drain trough 30, and is preferably inclined so as to direct the de-watered ice 13 by gravity into the upwardly open bucket 14. The scoop or bucket 14 is pivotally suspended upon a stationarily mounted pivot shaft 34 and may be provided with a drain spout 35; and the counterbalance weight 15 is adjustable along a scale beam 36 secured to the bucket 14 and formed for coaction with a fixed stop 37.

The thin tubular casing 16 within the lower end of which the rotor 21 is housed, has its lower tapered section 19 provided with an external supporting flange 37' formed for coaction with a lower closure plate 38, and the peripheral outlet opening 20 may be provided with an adjustable slotted slide 39 for varying the effective area of the discharge opening. The disintegrating and throwing rotor 21 comprises a flat circular disk secured to a central supporting and driving shaft 40 which is journalled in the lower plate 38 and is adapted to be rotated at variable high speed and in either direction. The throwing vanes 22 coact with the flat upper surface of the plate 38 and with the internal annular surface of the adjacent casing section 19, so as to prevent ice accumulation upon these surfaces, and these vanes 22 are adapted to throw the disintegrated ice tangentially and outwardly through the opening 20 in the form of relatively uniform and fine spray 41. The upwardly extending disintegrating blades 23 which are mounted centrally upon the rotor disk and project into the tapered casing section 19, revolve at relatively lower peripheral speed than the vanes 22 which are located farther from the rotor axis, and these blades 23 form a boring and disintegrating spire along which the mass of snow ice 13 must proceed before reaching the vanes 22.

During normal operation of the improved snow ice feeding, dewatering and distributing system, it is first desirable to properly adjust the setting of the blades 12, weight 15, and slide 39, and to regulate the speed of operation of the conveyor 5, cutter 11, and of the rotor 21, so as to produce the desired results. Slush ice may then be fed in the form of a stream 10 upon the upper forwardly advancing deck 8 of the conveyor 5, and will be carried upwardly and forwardly en masse as shown, so that the free liquid may escape by gravity through the trough hoppers 28 and spaces 32 to the trough 30 and drain spout 31. The de-watered ice 13 will eventually be carried around the discharge bend of the conveyor 5, where the bulk of the material will be removed by the revolving cutter 11 while the residual snow ice will be later removed by the scraper blade 12. The ice thus constantly removed from the conveyor 5, will drop by gravity into the bucket 14 wherein the remaining free liquid will escape through the spout 35, and whenever the bulk of material deposited into the bucket 14 is sufficient to raise the counter weight 15, a batch of de-watered snow ice 13 will be automatically dumped into the upper open end of the tubular casing 16. These successive equal charges of snow ice fall directly upon the disintegrating spire or blades 23 which are being revolved at high speed by the rotor 21; and due to the tapered formation of the lower casing section 19, most of the

disintegrated snow ice will drop freely toward the rapidly revolving peripheral rotor vanes 22, while the remainder will fall between the blades 23 and will ultimately be thrown into the path of the vanes 22 by the wider portions of the blades. As the disintegrated ice enters the path of the vanes 22, it is thrown violently outwardly and soon escapes through the outlet opening 20, tangentially and in the form of a uniform fan shaped spray 41 which may be mixed with concrete aggregate such as cement and sand or gravel, or otherwise utilized as desired. This delivery of ice spray 41 will be continuous if the mechanism is properly initially set or adjusted, and providing the supply stream 10 continues, and the spray 41 will be devoid of excess free liquid when discharged from the opening 20.

From the foregoing detailed description of the construction and operation of the improved system, it will be apparent that my present invention provides simple and highly efficient automatically functioning apparatus for converting relatively wet slush ice into a uniform continuous and relatively fine spray of snow ice. The improved conveyor 5 is especially adapted to handle slush ice having considerable excess water therein, and the improved batch transferring bucket 14 may readily be adjusted so as to vary the mass and the frequency of the successive batches of snow ice 13. The tilttable weighing bucket 14 obviously constitutes a uniform batch feed device for insuring proper delivery of relatively dry snow ice to the disintegrator at all times. This transfer bucket can obviously be provided with counter mechanism for recording the quantity of ice passing through the system, and the improved disintegrating and throwing rotor will effectively deliver the relatively dry snow ice received from the transfer bucket, regardless of the rate of supply of this material. The rotor construction is such that the snow ice cannot pack within the tubular casing 16, and the lower section 19 of this casing is so formed that the disintegrated ice will not lodge thereon and will fall freely into the path of the rapidly revolving vanes 22. These vanes 22 quickly deliver the disintegrated ice through the peripheral discharge opening 20, and by varying the size of this opening by adjustment of the slide 39, the shape and dimensions of the spray 41 can be varied to suit different conditions of use. The rotor 21 may also be revolved in either direction depending upon the desired direction of delivery, and the improved system is obviously simple and functions automatically after being properly adjusted and placed in operation. The apparatus can also be manufactured and operated at moderate cost, and has proven highly satisfactory and successful in actual use.

It should be understood that it is not desired to limit the invention to the exact details of construction or to the precise mode of use herein shown and described, for various modifications within the scope of the claims may occur to persons skilled in the art.

I claim:

1. In combination, an endless slat conveyor having an upper deck provided with a series of drainage hoppers and a semi-cylindrical delivery end adjoining said deck, means for constantly depositing a stream of relatively wet slush ice upon said deck remote from said delivery end, means coacting with said delivery end to constantly remove dehydrated snow ice therefrom, a casing formed to receive the snow ice from said

conveyor, a tilttable weighing bucket disposed beneath said conveyor delivery end and above said casing for automatically delivering successive measured batches of snow ice from the conveyor to the casing, and a rotor in said casing formed to initially disintegrate the snow ice and to thereafter deliver the same from the casing in the form of a uniform spray of finely divided dry snow ice.

10 2. In combination, an endless slat conveyor having an upper deck provided with a series of drainage hoppers and a semi-cylindrical delivery end adjoining said deck, means for constantly depositing a stream of relatively wet slush ice upon said deck remote from said delivery end, means coacting with said delivery end to constantly remove dehydrated snow ice therefrom, a casing formed to receive the snow ice from said conveyor, a uniform batch feed device disposed beneath said conveyor delivery end and above said casing for automatically delivering successive measured batches of snow ice from the conveyor to the casing, and a rotor in said casing formed to initially disintegrate the snow ice and to thereafter deliver the same from the casing in the form of a uniform spray of finely divided snow ice.

15 3. In combination, an endless slat conveyor having an upper deck provided with a series of drainage hoppers and a semi-cylindrical delivery end adjoining said deck, means for constantly depositing a stream of relatively wet slush ice upon said deck remote from said delivery end, means coacting with said delivery end to constantly remove dehydrated snow ice therefrom, a casing formed to receive the snow ice from said conveyor, a uniform batch feed device disposed beneath said conveyor delivery end and above said casing for automatically delivering successive measured batches of snow ice from the conveyor to the casing, and a rapidly rotating element in said casing formed to disintegrate the snow ice and to deliver the same from the casing in the form of a uniform spray.

20 4. In combination, an endless slat conveyor having an upper deck provided with a succession of convexly curved imperforate slats forming a series of drainage hoppers and a smooth semi-cylindrical delivery end adjoining said deck, means for constantly depositing a stream of relatively wet slush ice upon said deck remote from said delivery end, a revolving cutter coacting with said smooth delivery end to constantly chip dehydrated snow ice therefrom, a casing formed to receive the snow ice from said conveyor, a uniform batch feed device disposed beneath said conveyor delivery end and above said casing for automatically delivering successive measured batches of snow ice by gravity from the conveyor to the casing, and rotary means in said casing formed to initially disintegrate the snow ice and to thereafter deliver the same from the casing in the form of a uniform spray of finely divided dry snow ice.

25 5. In combination, an endless slat conveyor having an upper deck provided with a series of drainage hoppers and a semi-cylindrical delivery end adjoining said deck, means for constantly depositing a stream of relatively wet slush ice upon said deck remote from said delivery end, means coacting with said delivery end to constantly remove dehydrated snow ice therefrom, an upright tubular casing formed to receive the snow ice from said conveyor, a uniform batch feed device disposed beneath said

conveyor delivery end and above said casing for automatically delivering successive measured batches of snow ice from the conveyor to the upper open end of said casing, and a rotor in the lower end of said casing formed to initially disintegrate the snow ice and to thereafter deliver the same from the lower portion of the casing in the form of a uniform spray of finely divided dry snow ice.

6. In combination, an endless slat conveyor having an upper upwardly inclined deck provided with a succession of convexly curved imperforate slats forming a series of drainage hoppers and a smooth semi-cylindrical delivery end adjoining the uppermost end of said deck, means for constantly depositing a stream of relatively wet slush ice upon the lower end of said deck remote from said delivery end, a revolving cutter coacting with said smooth delivery end to constantly remove dehydrated snow ice therefrom, an upright tubular casing formed to receive the snow ice from said conveyor, a tilttable weighing bucket disposed beneath said conveyor delivery end and above said casing for automatically delivering successive measured batches of snow ice from the conveyor to the upper open end of said casing, and a rotor in the lower end of said cas-

ing formed to initially disintegrate the snow ice and to thereafter deliver the same from the lower portion of the casing in the form of a uniform spray of finely divided dry snow ice.

- 5 7. In combination, an endless slat conveyor having an upper deck provided with a series of drainage hoppers and a semi-cylindrical delivery end adjoining said deck, means for constantly depositing a stream of relatively wet slush ice upon said deck remote from said delivery end, means coacting with said delivery end to constantly remove dehydrated ice therefrom, an upright tubular casing having a constricted medial portion and being formed to receive the snow ice from said conveyor, a uniform batch feed device disposed beneath said conveyor delivery end and above said casing for automatically delivering successive measured batches of snow ice by gravity from the conveyor to the upper end of said casing above the casing constriction, and a rotor in the lower end of said casing below the constriction therein formed to initially disintegrate the snow ice and to thereafter deliver the same from the casing in the form of finely divided dry snow ice.
